UNITED STATES PATENT OFFICE

JOSEPH RUDRAUFF, OF UNION, NEW JERSEY.

SNOW-PLOW.

SPECIFICATION forming part of Letters Patent No. 398,283, dated February 19, 1889.

Application filed October 10, 1888. Serial No. 287,706. (No model.)

To all whom it may concern:

Be it known that I, JOSEPH RUDRAUFF, of the town of Union, in the county of Hudson and State of New Jersey, have invented certain new and useful Improvements in Snow-Plows, of which the following is a specification.

This invention relates to an improved snow-plow that is adapted for use on street and other railways, as it serves to cut up the snow in horizontal sections or slices and throw the same sidewise of the track, so as to clear the same in a quick and effective manner.

In the accompanying drawings, Figure 1 represents a side elevation of my improved snow-plow for street and other railways. Fig. 2 is a plan of the same. Fig. 3 is a front elevation of the same.

Similar letters of reference indicate corresponding parts.

Referring to the drawings, A represents my improved snow - plow, which is attached to either the front end of a locomotive or a track-cleaning car, A', said snow-plow being formed of a centrally-tapering cutter, A², and a number of blades, B B, which are arranged at an angle to the longitudinal axis of the locomotive or car and project outward from the sides of the tapering cutter A, said cutting-blades being arranged parallel to each other and at a slight upward inclination to the rails, so that the body of snow as it is cut in two by the centrally-tapering cutter passes along the laterally-extending cutter-blades and is cut up into a number of horizontal slices, which are delivered by the curved or scroll-shaped outer ends, B', of the cutter-blades sidewise of the track. The cutter-blades B are supported by an angular supporting-frame, C, the tapering side walls of which are securely attached to the locomotive or car. At the outer rear ends of the cutter-blades B are arranged guard plates or wings D, which are rigidly secured to the end walls, C, of the frame and extend at right angles thereto, but are parallel to the inclined side walls of the blade-body,

as shown clearly in Fig. 2. These wings or guard-plates serve for throwing the slices of snow as the same are cast by the curved ends of the blades still farther away from the track, so as to prevent the crowding in of the mass of snow toward the rails and the track.

B' is the top plate of the apparatus.

My improved snow - plow is specially intended for use on street-railways, from which the snow is to be removed by the plow shortly after the fall of the same and before the same has settled into a compact mass, as before settling it can be cut up into slices and effectively moved from the track and laid up alongside of the same. In case of double tracks the cutter A is located at the inner side of the track, the inclined cutting-blades extending in this case diagonally across the track.

Having thus described my invention, I claim as new and desire to secure by Letters Patent—

1. A snow-plow for railways, consisting of a centrally-tapering cutter having a continuous vertical cutting-edge at its front end and a number of superposed cutter-blades extending laterally from said cutter at an inclination to the axis of the cutter and being outwardly curved at their upper and rear ends, substantially as set forth.

2. A snow - plow formed of a supporting-frame having a centrally-tapering cutter, and a series of superposed cutter-blades that extend from the cutter laterally at a suitable angle of inclination to the axis of the same, said cutter-blades being bent over or curved at their upper rear ends and provided with guard-plates or wings at their outer ends parallel to the side walls of the plow-body or cutter, substantially as set forth.

In testimony that I claim the foregoing as my invention I have signed my name in presence of two subscribing witnesses.

JOSEPH RUDRAUFF.

Witnesses:

CARL KARP,
JOHN A. STRALEY.
